UNITED STATES PATENT OFFICE.

NELS A. NELSON, OF BODE, IOWA, ASSIGNOR TO BACO ELECTRIC CO., OF BODE, IOWA,
A CORPORATION OF IOWA.

ELECTRIC HEATING IRON.

1,425,040.

Specification of Letters Patent. Patented Aug. 8, 1922.

Application filed May 24, 1919. Serial No. 299,630.

To all whom it may concern:

Be it known that I, NELS A. NELSON, a citizen of the United States, residing at Bode, in the county of Humboldt and State 5 of Iowa, have invented certain new and useful Improvements in Electric Heating Irons, of which the following is the specification.

This invention relates to heating irons of 10 the type heated by an electric arc.

Among the objects of my invention is the provision of an electric heating iron embodying general improvements in construction; further, to provide a novel form of operating 15 switch, in which the adjustment of the movable carbon and the making or breaking of the electric circuit may be simultaneously accomplished by one operation; further, an arrangement in which the retracting of the 20 adjustable carbon will automatically open the switch controlling the electric current; further, an automatic closing of the switch controlling the current upon a forward movement of the adjustable carbon; further, 25 the provision in the hollow head of an air opening through the side walls to permit the entry of air to increase the efficiency of the arc; further, to effect improved means for extending the effective length of the 30 slidable carbon as it becomes shortened with relation to its supporting stem by use; further, to provide a more simple, economical, and efficacious device of the class described; and such further objects, advantages, and capabilities as will later more fully appear.

My invention further resides in the combination, construction, and arrangements of parts illustrated in the accompanying drawing, and while I have shown therein a preferred embodiment, I desire it to be understood that the same is susceptible of modification and change without departing from the spirit of my invention.

In the drawings:

45 Fig. 1 is a side elevation of a heating iron embodying my invention.

Fig. 2 is a longitudinal sectional view of Fig. 1, and taken on a central plane.

50 Fig. 3 is a transverse sectional view of Fig. 1 and taken on a plane passing through the switch operating button.

Referring to the drawing, it will be seen that my improved heating iron comprises a head 1, provided with the bore 2, in the bottom of which is seated the fixed carbon 3,

just above which, and opposite the region of formation of the arc to be hereinafter referred to, is formed through the wall of the head 1 the aperture 4 to permit the passage of air therethrough to increase the efficiency 60 of the arc. Mounted in the head 1 at the open end of the bore 2 is the insulating ring 5, formed with a central opening 6, through which slidably passes the longitudinally adjustable carbon 7, secured at its upper end 65 within the hollow adjusting stem 8 by means of the small set screw 9 mounted in the ring 10, which in turn is slidably mounted on the stem 8. Loosening of the set screw 9 will permit the carbon 7 to be moved with relation to both the ring 10 and the stem 8, and movement of the ring 10 with relation to the stem 8. This arrangement, as is obvious, will permit adjustment of the carbon 7 and ring 10 with relation to the stem 8, whereby as 70 the length of the carbon is decreased by use, these parts may be appropriately adjusted to accommodate the same, after which the screwing of the setscrew against the carbon will hold the parts together in fixed relation. 75

The adjusting stem 8 is preferably formed of a tube 11 having its material cut away for a portion of its length at 12 to expose the carbon 7. The upper end of the tube 11 is filled with the plug 13 for a purpose to be later described. Secured to the upper end of the head 1 is the metal shank 14, preferably of tubular formation at its ends 15 and 16, the former of which is suitably fixed in a seat formed in the head 1 and the latter of which 90 is fixed in position on the reduced portion 17 of the wooden handle 18. An elongated opening is formed in the tube 14 opposite the setscrew 9, whereby to give free access for adjustment of the carbon 7 within the ring 10 and hollow stem 8.

The handle 18 is formed throughout its length with the central opening 19 within a slight enlargement, at the lower end of which is snugly seated the sleeve 20, formed 100 in one side of which is the elongated slot 21, so positioned as to register with the slot 22 formed in the handle 18. The handle 18 is provided in one side with the groove 23 lying directly over and of greater width 105 and length than slot 22 as seen in Figs. 2 and 3. Over the groove 23 to cover the same is secured the plate 24 formed of material that is a non-conductor of electricity, and having therein the slot 25 posi- 110

tioned directly over slot 22. Secured in the bottom of groove 23 back of the slot 22 is the metal plate 26 to the back end of which is connected the wire 27, forming one path of the electric circuit while the wire 28, forming the other path of said circuit is connected with the inner end of the sleeve 20. The wires 27 and 28 will be connected at their other ends to any suitable source of electricity.

Secured into the plug 13 of the adjusting stem 8 is a post 29 of a length sufficient to extend through slots 21, 22, and 25, and carrying upon its outer end the button 30, also formed of insulating material. As noted in Fig. 3, the bottom of the button 30 is reduced in diameter and extends through an aperture in the metal switch plate 31, which is slidably mounted in groove 23 and is of arched formation longitudinally whereby the end 32 will at all times be in sliding contact with plate 26, while end 33 will contact with ring 16 of shank 14 when button 30 is moved toward the bottom (left hand end in Fig. 2) of slot 22, but will rest upon the wood seat 34 when button 30 is pushed in the opposite direction. Since the reduced lower end of insulating button 30 passes through the aperture in switch plate 31, it will be apparent that no short circuit can be formed through post 29, but all of the current is compelled to pass from wire 27 through plate 26, switch plate 31, and into shank 14 when button 30 is in the position shown in Fig. 2.

It is important to note that post 29, when moved in slot 22, will cause simultaneous movement in the same direction of both carbon 7 (through the medium of stem 8) and switch plate 31. This means that by suitably adjusting carbon 7 with relation to stem 8, that when carbon 7 is moved into proper position for the formation of an arc between the two carbons, the switch plate 31 will automatically be moved to bring its end 33 into contact with ring 16 of shank 14, to thereby complete the circuit.

In the operation of my heating iron, assuming the carbon 7 to be properly adjusted with relation to stem 8, wires 27 and 28 connected to a suitable source of electricity, and switch 31 to stand open, it will be seen that movement of button 30 to bring carbon 7 into contact with fixed carbon 3 will automatically close the switch as described above and complete the electric circuit through wire 27, plate 26, switch 31, shank 14, head 1, carbons 3 and 7, stem 8, sleeve 20, and wire 28. From this it will be seen that the current can be passed through carbon 7 and upon slight movement backward thereof, after contacting carbon 3, will create an electric arc between these carbons the length of which arc can be controlled by movement of the button 30. The

arc thus set up will create intense heat within the head 1, which within a short time will be brought to a sufficiently high temperature to perform soldering or other operations for which the iron may be intended. The opening 4 in the head 1 creates more or less ventilation within the bore 2 and increases the efficiency of the arc. The iron will operate quite successfully, however, without aperture 4 and the same may be omitted if desired.

While I have described the handle 18 as being of wood, it is obvious that the same may be formed of any other suitable material that is a non-conductor of electricity. Also the various other parts may be made from a variety of materials without departing from the spirit of my invention, the essential requirement being that those parts that are to transmit the electricity be conducting in nature and those parts intended not so to do be of non-conducting material. It is further to be understood that, while I have disclosed my invention as being embodied in a soldering iron, it is not to be strictly limited thereto, since it is capable of application to any class of tool having a head or other part that is susceptible of being heated with an electric arc.

Having now described my invention, I claim:

1. In a device of the class described, a hollow head having means therein for the creation of an electric arc, said means comprising a longitudinally adjustable carbon, a handle connected to said head, and manually operated means on said handle for simultaneously adjusting said carbon and automatically controlling the electric circuit leading to the carbons.

2. In a device of the class described, a hollow head, a carbon longitudinally adjustable therein, a handle having manually operated means for completing an electric circuit through said carbon and head, and means on said handle for moving said carbon and simultaneously therewith automatically making or breaking said circuit by actuating said first named means.

3. In a device of the class described, a hollow head, a carbon longitudinally adjustable therein, a handle having a switch associated therewith, means for adjusting said carbon, said switch being automatically operated upon movement of said carbon.

4. In a device of the class described, a hollow head having a stationary pole and a slidible pole therein, a handle, means associated with said handle for adjusting said slidible pole, a switch, said switch and said means being so connected that movement of one operates the other.

5. In a device of the class described, a hollow head having a stationary pole and a

- slidable pole, a handle, a stem slidably mounted in said handle and fixed to said slidable pole, means for sliding said stem, and a switch automatically operated as said stem is moved.
6. In a device of the class described, a hollow head having a fixed pole and a slidable pole, a shank, a handle on said shank, a stem slidably mounted in said handle and fixed to said slidable pole, a slot in said handle, a post in said stem extending through said slot, a groove in the handle overlying said slot, a sliding switch in said groove adapted when slid to make or break an electric circuit through said head, means to insulate said switch from said post, longitudinal movement of said post simultaneously sliding said slidable pole and controlling said switch.
- 10 7. In a device of the class described, a hollow head having a fixed pole and a slidable pole therein, a shank, a handle on said shank, a stem fixed to said slidable pole and slidably in said handle, a post on said stem and extending through a slot in said handle, and a switch associated with said handle for automatic operation as said post is moved in said slot to slide said slidable pole in said head.
- 15 8. In a device of the class described, a hollow head having a fixed pole and a slidable pole therein, a handle, a stem slidably in said handle and carrying at one end said slidable pole, means for securing said slidable pole to said stem, said means being adjustable to permit said last mentioned pole to be extended with relation to said stem as the pole becomes shortened by use.
9. In a device of the class described, a hollow head having a fixed pole, a handle, a stem slidably mounted at one end in said handle and carrying at its other end a second pole extending into the hollow of said head but insulated from the sides thereof and adapted to cooperate with said fixed pole to produce an electric arc in said head, means for adjustably securing said second pole to said stem, a switch for controlling an electric circuit through said head and poles, means for sliding said stem in said handle, the operation of said last mentioned means automatically operating said switch so that when said poles are brought together, the switch will be closed, and when moved apart, the switch will be opened.
- 10 10. In a device of the class described, a hollow head, poles in said head for the production of an arc when traversed by an electric current, and an opening through the wall of said head opposite the region of formation of said arc to permit the passage of air to and from the arc.
- 15 11. In a device of the class described, a hollow head having a fixed pole therein, a handle, a stem slidably associated with said handle and carrying a second pole, and means connected with said stem adapted to be engaged by the finger or thumb of the user to slide said stem and second pole.

In witness whereof, I hereunto subscribe my name to this specification in the presence of two witnesses.

NELS A. NELSON.
